UNITED STATES PATENT OFFICE.

MISAEI DELUDE, OF NORTH BROOKFIELD, MASSACHUSETTS.

MACHINE FOR VENDING POSTAGE-STAMPS.

No. 823,769.

Specification of Letters Patent.

Patented June 19, 1906.

Application filed December 7, 1905. Serial No. 290,667.

To all whom it may concern:

Be it known that I, MISAEI DELUDE, a citizen of the United States, residing at North Brookfield, in the county of Worcester and State of Massachusetts, have invented a new and useful Machine for Vending Postage-Stamps, of which the following is a specification.

This invention relates to a coin-controlled machine for vending postage-stamps.

The especial object of this invention is to provide a simple and efficient form of vending-machine which will permit the operator by use of a suitable coin or coins to procure a single postage-stamp or successive postage-stamps from repeated operations of the machine, whereby persons will be enabled to properly stamp and mail letters or other mail-matter without requiring personal attention of a salesman.

Further objects of this invention are to provide a novel and simple form of coin-controlled slide which will operate the desired apparatus only when the proper coin or coins are used, to provide a simple and efficient form of feed mechanism for feeding out and delivering successive stamps, and to provide an automatic stop preventing coins being inserted after the supply of stamps is exhausted.

To these ends this invention consists of the postage-stamp-vending machine and of the combinations of parts therein, as hereinafter described, and more particularly pointed out in the claims at the end of this specification.

In the accompanying three sheets of drawings, Figure 1 is a plan view of a postage-stamp-vending machine constructed according to this invention, the cover of the casing being removed and part of the coin-slide being shown in position to be inserted into the machine. Fig. 2 is a longitudinal sectional view of the same. Fig. 3 is an end view thereof. Fig. 4 is a transverse sectional view. Fig. 5 is a fragmentary view, partly broken away, of the slide. Fig. 6 is a detail view of the stop-piece. Fig. 7 is a detail view of the catch-piece for retaining the coin or coins. Fig. 8 is a detail view of the feed-pawl for advancing the feed-belt; and Figs. 9 to 12, inclusive, are fragmentary plan views illustrating the operation of the machine. In Fig. 9 the operating-slide is being inserted, in Fig. 10 it is shown pushed in far enough to have operated the machine, in Fig. 11 the slide is being withdrawn, the coins being retained in

the machine, and in Fig. 12 the operating-slide has been completely withdrawn and the feelers or fingers thereof have resumed their position, which will prevent the slide from being inserted to operate the device.

Referring to the accompanying drawings and in detail, as shown in Figs. 1 and 2, the operative parts are preferably housed within a box or casing C. The casing may, if desired, be provided with a hinged cover, as shown in Fig. 3.

The stamps, which are to be delivered one at a time, are wound upon a spool or drum 15, and from the spool 15 the string of stamps W pass under the guide-roll 16 and up over the stop device for preventing the operation of the machine when the supply of stamps fails. The construction of this stop device is most clearly illustrated in Fig. 4. As shown in this figure, a standard 17 is provided with a guide-bracket 18. Pivoted in the standard 17 is a cut-off plate having a part 19 and an arm 20, guided in the bracket 18. The stamps W pass over the arm 20 and normally hold the plate 19 up out of the way. From the automatic cut-off device the stamps pass through a guide 21 and between the delivery-rolls 22 and 23, which are preferably geared to turn together.

Wrapped around the top delivery-roll 22 is an operating-belt 24, which operating-belt 24 is provided with properly-spaced sockets or recesses 25. At its other end the belt 24 passes over the roll 26. To advance the belt 24 the proper distance to deliver a single one of the stamps W, I employ an operating-pawl 27. (Shown in Fig. 8.)

As shown in Fig. 1, the operating-pawl 27 is carried by a slide 28, movable upon guide-ways 29 and normally forced back by a spring 30. The distance that the slide 28 may be advanced to feed out or deliver a stamp is preferably regulated by side stops, so that exactly one stamp will be delivered for each operation of the machine.

The feeding-out operation is effected by means of a hand-operated slide which can be pushed into the machine to operate the pawl 27 only when the same contains the required coin or coins. The details of this slide or key and the manner in which the same co-operates with a fixed stop-piece form essential parts of this invention.

As shown in Fig. 1, the body portion of the slide or coin-carrier 36 is provided with end

feelers or keys 37 and center feelers or fingers 38. As shown in Fig. 5, the feelers 38 are pivoted and will normally stand in a tipped position. At the side of the body portion of the slide 37 are spring-arms 39. As shown in Fig. 12, the spring-arms 39 may be expanded and the feelers 38 held in horizontal position by inserting the proper coin or coins in the slide. For example, as shown in Fig. 1, 10 by placing two pennies or coins P side by side and inserting them below a cover-plate 40 the parts will be made to occupy the required relative position to operate the machine. The coins P are located immediately below slots 15 41, permitting the entrance of the downwardly-extending points of a detent to prevent the coins from being drawn back out of the machine.

As shown in Fig. 6, the stop-piece which 20 co-operates with the hand-slide is provided with outside perforations 45 for receiving the feelers or fingers 37 and with inside perforations 46 for receiving the feelers or fingers 38. The stop-piece 42 is located in position in the 25 machine so that a space 43 will be left at each side thereof to receive the projecting arms 39. The stop-piece 42 is located in line with a slideway formed of pieces 32 and which opens through the end of the casing 30 with an opening 31, as shown in Fig. 3.

Pivottally mounted above the slideway is a catch-piece 34, (shown in detail in Fig. 7,) which is pivottally mounted and provided with a spring 35. The catch-piece 34 serves 35 to retain the coins in the machine when the hand-operated slide is withdrawn, and, as shown in Figs. 3 and 4, the coins may be allowed to drop down into a receptacle or pocket R, having a locked door D.

40 Considering now the operation of a vending-machine as constructed for the sale of two-cent stamps, two pennies will first be put into the hand-operated slide, as shown in Fig. 9. The hand-operated slide can then be 45 pushed into the machine, the side pieces of the slide being spread far enough apart to pass the stop-piece and the pivoted feelers be held up by the coins to register with the perforations of the stop-piece. This will permit 50 the hand-operated slide to be pushed in so that the side pieces thereof will move forward the carrier 28, which, through the pawl 27, will advance the feed-belt and deliver a single stamp from the machine. When the slide is 55 withdrawn, as shown in Fig. 11, the coins will be retained in the machine, and the feelers or fingers of the slide will resume their normal positions, as shown in Fig. 12, whereby the slide cannot be again used for operating the

machine until the proper coin or coins are 60 used in connection therewith.

I have illustrated the form of machine which would be employed for selling or delivering two-cent stamps. By using a greater or less number of coins a machine constructed 65 according to this invention may be adapted for delivering stamps of different denominations.

Having thus fully described this invention and the manner in which the same is to be 70 performed, what is claimed, and sought to be protected by Letters Patent of the United States, is—

1. An apparatus of the class described, comprising a pusher-slide having side pieces 75 which swing in toward the slide, and pivoted fingers which normally hang at an angle to the length of the slide, the side pieces and fingers being mounted to be held in operative position by coins of the proper dimensions. 80

2. In an apparatus of the class described, the combination of a pusher-slide having pivoted fingers which normally hang at an angle to the length of the slide, said fingers being mounted to be held in operative position by 85 coins of a proper dimension, and a stop-piece having openings for registering with said fingers only when the same are held in place by coins.

3. In an apparatus of the class described, 90 the combination of a pusher-slide having side pieces which swing in toward the slide, and pivoted fingers which normally hang at an angle to the length of the slide, the side pieces and fingers being mounted to be held in operative position by coins of the proper dimensions, and a stop-piece having openings for registering with the movable pieces or feelers of the slide only when the same are held in place by coins. 95

4. In a machine for vending postage-stamps, the combination of feed-rolls, coin-controlled means for operating the feed-rolls, and an automatic stop for preventing coins from being inserted when the supply of stamps 105 is exhausted, said stop comprising a pivoted member having a blade adapted to move into position for intercepting the coins, and a rearwardly-extending projection normally held down by the stamps in the machine. 110

In testimony whereof I have hereunto set my hand in the presence of two subscribing witnesses.

MISAEI DELUDE.
